UNITED STATES PATENT OFFICE

2,437,720

METHOD OF AND APPARATUS FOR MEASURING THE COMPOSITION OF GAS

Robert A. Ackley, Chicago, Ill., assignor to Republic Flow Meters Company, Chicago, Ill., a corporation of Illinois

Application June 14, 1943, Serial No. 490,736

9 Claims. (Cl. 73—25)

1

This invention relates to method of and apparatus for measuring the composition of gas and more particularly to the measurement of the oxygen content of a gas.

Heretofore gas, such as flue gas or engine exhaust gas, has been analyzed in an Orsat apparatus which is slow and cumbersome to operate and which does not give a continuous or instantaneous indication of the composition.

One of the principal objects of the present invention is to obtain an instantaneous and continuous indication of the composition of a gas by observing the flame temperature produced by burning a mixture of the gas with a combustible.

Another object is to provide a method and apparatus for measuring the composition of a gas in which variations in flame size do not affect the measurement.

Still another object is to compensate for variations in the combustible supply.

The above and other objects and advantages of the invention will be more readily apparent from the following description when read in connection with the accompanying drawing, in which—

Figure 1 is a diagrammatic side elevation with parts broken away illustrating one apparatus for carrying out the invention;

Figure 2 is a similar view of an alternative apparatus;

Figure 3 is a partial view similar to Figure 1 of still another form of apparatus;

Figure 4 is a partial plan view of the apparatus of Figure 3; and

Figure 5 is a view similar to Figure 1 of an additional form of apparatus.

As shown in Figure 1, the apparatus comprises a burner tube 10 having an enlarged base 11 forming a mixing chamber for a combustible gas and a gas whose composition is to be measured. The combustible gas is supplied to the mixing chamber through a pipe 12 projecting into the chamber and the gas to be analyzed is supplied through a pipe 13 opening into the side of the mixing chamber. With this construction, the combustible gas will tend to aspirate the gas to be measured into the burner and the proportions of the two gases can be controlled by regulating their respective pressures or in any other desired manner.

The mixture of the gases supplied to the burner burns in a circular flame indicated at 14 having in its interior the usual cone 15 in which no combustion occurs.

I have found that the temperature of the flame

2

varies substantially directly with the percentage of oxygen in the sample gas and that a very accurate indication of the oxygen in the sample gas can be obtained by measuring the flame temperature. For this purpose, as shown in Figure 1, a thermocouple 16 is inserted in the flame and is connected to a millivoltmeter 17 which may be calibrated to read directly in terms of percentage of oxygen.

10 In order to obtain an accurate indication of the flame temperature regardless of variations in flame size, the thermocouple is mounted above and out of line with the axis of the tube 10 so that it will lie in the base of the flame adjacent 15 the cone 15. With the thermocouple located in this position, variations in the flame size have substantially no effect on the temperature indication and an accurate measurement of the oxygen percentage in the sample gas is obtained 20 without requiring close regulation of the volume of sample gas and combustible gas supplied.

Figure 2 shows another construction similar to that of Figure 1 and parts therein corresponding to like parts in Figure 1 have been designated 25 by the same reference numerals. In this construction, the temperature of the flame is measured by a resistance element 18 which is mounted above the tube 10 to lie around the flame. The element 18 is formed of a material whose 30 resistance changes in response to changes of temperature and is connected in one leg of a bridge circuit indicated generally at 19 so that the bridge circuit will be unbalanced in response to changes in the resistance 18. Unbalance of the bridge circuit is indicated by a millivoltmeter 21 which can be calibrated to read directly in terms of percentage of oxygen in the sample gas.

40 Still another construction is shown in Figures 3 and 4 in which a curved bimetal strip 22 is anchored at one end at 23 and lies around the flame 14. The free end of the strip carries a pointer 24 moving over a scale 25 which can be calibrated to indicate directly the percentage of 45 oxygen in the sample. In this construction the strip will flex in response to temperature variations to indicate on the scale the percentage of oxygen in the sample.

Figure 5 illustrates a construction in which compensation is provided for variations in the combustible gas, parts therein corresponding to like parts in Figure 1 being indicated by the same reference numerals. In this construction a second burner 26 is provided supplied with combustible 55 gas through a pipe 27 and with air or like flame

supporting gas of known composition through a pipe 28. The burner 26 produces a flame 29 and thermocouples 31 and 32 are mounted respectively in the flames 14 and 29. Similar terminals of thermocouples 31 and 32 are connected by a wire 33 and the other terminals are connected through a millivoltmeter 34. With this circuit the thermocouples are bucking and the millivoltmeter 34 will measure the difference between the voltage generated thereby which is proportional to the difference in the flame temperatures. Thus any variation in the combustible gas will produce a similar variation in the temperature of both flames and the millivoltmeter will be effected only by changes in the temperature of the flame 14 caused by variations in the oxygen content of the gas sample. It will be understood that similar compensation could be produced using a bridge circuit as shown in Figure 2 or various other measuring or indicating methods.

While several embodiments of the invention have been shown and described in detail herein, it will be understood that these are illustrative only and are not intended to be taken as a definition of the scope of the invention, reference being had for this purpose to the appended claims.

What is claimed is:

1. The method of measuring the oxygen content of a gas sample which comprises mixing the gas sample with a combustible gas, burning the mixture in air to produce a substantially circular flame, and measuring the temperature of the flame adjacent its base.

2. The method of measuring the oxygen content of a gas sample which comprises mixing the sample with a combustible gas in predetermined proportions, burning the mixture in air to produce a flame, and measuring the temperature of the flame.

3. The method of measuring the oxygen content of a gas sample which comprises mixing the sample with a combustible gas in predetermined proportions, burning the mixture to produce a flame, burning a mixture of the combustible gas and air to produce a second flame, and measuring the difference in temperatures of the flames.

4. Apparatus for measuring the composition of a gas sample comprising means for mixing the gas sample with a combustible gas, a burner to burn the mixture, a resistance above the burner whose value varies in accordance with variations in temperature, and means to measure the value of the resistance.

5. Apparatus for measuring the composition of a gas sample comprising means for mixing the gas sample with a combustible gas, a burner to

burn the mixture, a resistance above the burner whose value varies in accordance with variations in temperature, a bridge circuit in which the resistance is connected, and means to measure the unbalance of the bridge circuit.

6. Apparatus for measuring the composition of a gas sample comprising means for mixing the gas sample with a combustible gas, a burner to burn the mixture, a bimetal strip above the burner to be responsive to a flame issuing therefrom, and means to indicate the deflection of the strip.

7. Apparatus for measuring the composition of a gas sample comprising means for mixing the gas sample with a combustible gas, a burner to burn the mixture, a second burner to burn a mixture of the combustible and air, and means to measure the difference in temperatures of the flames issuing from the two burners.

8. Apparatus for measuring the composition of a gas comprising a burner tube, means for supplying gas to be measured and a combustible gas to the burner tube in predetermined proportions, and temperature sensitive means mounted above and displaced from the axis of the tube to lie in the base of the flame to respond to changes in the temperature of a flame issuing from the tube.

9. Apparatus for measuring the composition of a gas comprising a burner tube, means for supplying gas to be measured and a combustible gas to the burner tube, a thermocouple above and adjacent one side of the tube to lie in the base of a flame issuing therefrom, and means to measure a function of the voltage generated by the thermocouple.
